DESIGN FOR A STORAGE BATTERY CASE

Willard L. Reinhardt, Shaker Heights, Ohio, assignor to Willard Storage Battery Company, Cleveland, Ohio, a corporation of West Virginia

Application February 23, 1937, Serial No. 67,800

Term of patent 14 years

To all whom it may concern:

Be it known that I, Willard L. Reinhardt, a citizen of the United States and a resident of Shaker Heights, in the county of Cuyahoga and State of Ohio, have invented a new, original, and ornamental Design for a Storage Battery Case, of which the following is a specification, reference being had to the accompanying drawing, forming a part thereof, in which

Fig. 1 is an end view of a storage battery case showing my new design; and

Fig. 2 is a side view of the same.

The side and end portions not shown in the drawing are of the same design as those shown.

I claim:

The ornamental design for a storage battery case substantially as shown and described.

WILLARD L. REINHARDT.
